UNITED STATES PATENT OFFICE.

CLARENCE R. EATON, OF COLDWATER, KANSAS.

ENGINE.

1,361,521.

Specification of Letters Patent.

Patented Dec. 7, 1920.

Application filed May 3, 1918. Serial No. 232,364.

To all whom it may concern:

Be it known that I, CLARENCE R. EATON, a citizen of the United States, residing at Coldwater, in the county of Comanche and State of Kansas, have invented certain new and useful Improvements in Engines, of which the following is a specification.

This invention relates to internal combustion engines, and more particularly to an engine provided with a mechanism for supplying lubricant to the bearing surfaces.

One of the main objects of the invention is to provide an internal combustion engine of comparatively simple construction provided with simple and efficient means for supplying lubricant to the bearing surfaces. A further object is to provide a lubricating unit so mounted as to permit removal of the lower section of the crank casing without necessitating demounting or disassembling of the lubricating means. A further object is to provide trough-like members in combination with dipping elements or ladles carried by the connecting rods of the pistons operative in the trough members for dipping oil therefrom when the connecting rods are reciprocated, means being provided for supplying lubricant to the troughs. Another object is to provide a pump of simple construction and operation which is so associated with the lubricating unit as to be readily detachable, when necessary. Further objects will appear from the detailed description.

35 In the drawings:

Figure 1 is a central sectional view through an engine constructed in accordance with my invention.

Fig. 2 is a view in side elevation of the upper portion of the engine.

Fig. 3 is a transverse section through the upper section of the crank casing, showing the supporting bracket for the pump and the manner of mounting the same.

45 Fig. 4 is a transverse section through the crank case taken in a plane adjacent one end thereof, the cylinder being shown in elevation.

Fig. 5 is a detail of the eccentric for operating the pump.

Fig. 6 is a detail of the pump supporting bracket.

Fig. 7 is a detail of one of the oil cups for the cam shaft.

55 Fig. 8 is a detail of the mounting of the oil distributing pipe upon the pump.

Engine base 1 may be of any suitable construction and is adapted to be mounted on the frame of an automobile or similar vehicle in the usual manner. This base is 60 provided with suitably spaced openings in which are secured the lower ends of the cylinders 2. Each of these cylinders is provided with an outer water jacket 3 and a cylinder head 4 secured thereon by means 65 of bolts 5, this head being provided with inlet and exhaust openings controlled by the valves 6 and 7, respectively. These valves are held in raised position, normally, by expansion coil springs 8 mounted about 70 the valve stems and confined between the engine head and disks 9 secured on the valve stems adjacent the upper ends thereof.

A radiator 10 of any suitable construction is connected by means of a pipe 11 to 75 the water space of the front cylinder adjacent the lower end of the water jacket 3, the upper end or top of the radiator being connected by a pipe 21, to the cylinder at the upper end of the water space. The 80 water spaces of the two cylinders are connected by means of the tubular members 13 each provided with a union 14 so as to permit the cylinders to be independently detached from base 1. Each cylinder is further provided, adjacent its lower end, with 85 an outer annular flange 15 which is provided with a plurality of spaced apertures to receive securing screws 16 which are threaded into the base 1 thus detachably securing the cylinders to the base. By removing these securing screws, the cylinders may be independently removed from the engine base so as to permit ready access to the interior of the cylinders and to the interior of the engine base and crank casing carried thereby. In this manner, either one or both of the cylinders may be readily removed for repairs, cleaning, or other purposes.

100 A piston 17 is operative in each cylinder and is connected by a connecting rod 18, to a crank shaft 19 rotatably supported in the base 1. The lower plate 20 of the bearing sleeve of the connecting rod 18 is provided 105 with a downwardly directed substantially triangular dipper 21 the apex of which is directed downwardly. This dipper is in vertical alinement with an arcuate trough 22 which is of substantially semi-circular shape, 110 the ends of this trough being secured to the base 1 adjacent the lower edge thereof.

When the engine is in operation, the dippers 21 will be lowered into the trough 22 and moved through the same, these dippers being then raised out of the trough and moved in a reverse direction so as to discharge the oil or other lubricant contained thereby.

Each of the troughs 22 is provided, at its lowermost point, with an opening which receives a nipple 23 carried by a T 24 which is interposed in an oil pipe 25. This oil pipe communicates at its lower end with the main bearing indicated generally by 26 of the main crank shaft 19. At its inner end, 10 the pipe 25 communicates with a T connection 27 which is threaded onto the lower end of the cylindrical discharge spout 28 of an oil pump 29. Oil is supplied by this pump to the trough 22 and to the main bearings 15 26, when the pump is operated, so as to insure proper lubrication of the bearing.

The body of pump 29 is divided by a central web 30 into an intake chamber 31 and an exhaust chamber 32. The lower end 20 of the intake chamber 31 tapers downwardly to provide a seat for a ball valve 33 mounted therein which controls the intake opening 34. Upward movement of this valve is positively limited by a rod 35 which 25 extends across the lower portion of the intake chamber above the valve. A suitable screen 36 is screwed onto the lower end of the intake chamber and, when the pump is in operative position, this screen projects 30 into an oil well formed in the crank casing 38. An upwardly projecting wall 39 is formed in the intake chamber 32, this wall serving with web 30 to provide a valve chamber which receives the ball valve 40 for controlling communication between the intake 35 and exhaust chambers, upward movement of this valve being positively limited by a rod 41 similar to rod 35. A piston 42 is operative in the barrel 43 of the pump, this 40 piston being connected by a piston rod 44 to an eccentric disk 45 keyed on a cam shaft 46 rotatably supported in the base 1. The eccentric disk 45 is provided with a central peripheral groove which forms lateral retaining flanges between which is mounted a connecting strap or collar 47 which serves to loosely connect the upper end of the piston rod 44 to the disk in the well known manner. A spur gear 48 is keyed on cam 45 shaft 46 and meshes with a similar gear 49 keyed on the crank shaft 19. In this manner, when the crank shaft is rotated, the cam shaft will be rotated so as to reciprocate the piston of the pump thus drawing 50 oil into the intake chamber 31 and forcing this oil into and through the exhaust chamber 32 to the main bearing of the crank shaft and to the trough 22. To permit removal 55 of the gear 49, one crank 50 of the crank shaft 19 is detachably secured to the body

portion of the shaft, as will be clear from Fig. 1 of the drawings.

The pump 29 is supported by a bracket 51 which is shaped to fit about one side and the top of the pump, the upper end of this bracket being bifurcated to fit about the lateral faces of a bearing beam 52 extending transversely of the base 1, this beam being provided with lateral recesses to receive the arms at the upper end of the bracket. This bracket is detachably secured to the beam by securing bolts inserted through the arms of the bracket and threaded into the beam, and the pump is similarly secured to the bracket so as to be detachable therefrom. The pump 80 and the parts associated therewith constituting the lubricating unit are thus all supported by the base 1 so that the lower section of the crank casing 38 may be removed without disturbing the lubricating unit thus 85 permitting ready access to the same. The central bearing for the main crank shaft will be thoroughly lubricated by the oil which is splashed thereon during the operation of the engine due to the action of the dippers 90 21 in the troughs 22.

Cam shaft 46 is provided with a plurality of cams 53 secured thereon which engage the lower ends of operating rods or plungers 54 which are reciprocably mounted in the upper 95 section of the crank casing, a rod 55 being adjustably secured to member 54 at its lower end, this rod being operated through a bracket 56 projecting from the engine head 4. The upper end of rod 55 is of rounded 100 or substantially spherical shape and is operative in a corresponding recess in the outer end of a rocker arm 57 which is rockably mounted for movement about a horizontal axis in a supporting frame 58 formed by an 105 extension of one of the securing bolts 5. The inner end of rocker arm 57 engages the upper end of the valve stem so as to depress the valve when the outer end of the arm is raised, the valves being depressed and raised 110 in succession so as to admit an explosive mixture to the cylinders, and permit the products of combustion to be expelled therefrom, in the usual manner.

A stub shaft 59 is rotatably mounted adjacent the forward end of casing 1 in axial alignment with the crank shaft 19. This stub is connected directly to the crank shaft so as to be rotated thereby. A flange pulley 60 is secured on the forward end of stub 120 shaft 62 secured on the fan shaft 63 rotatably supported in the fan bracket 64 secured to the casing 1 adjacent the front thereof. A fan 65 of suitable construction is secured on shaft 63. In this manner, rotation is imparted to the fan direct from the crank shaft. A bevel gear 66 is secured on stub shaft 59 and meshes with a similar gear 67 disposed laterally of the shaft which may be utilized for driving a belt pulley when it is 130

desired to use the engine for belt work, or for any similar purpose desired. Crank shaft 19 is provided, at its other end with a substantially disk shaped head 66 to which is secured the fly wheel 67. Fly wheel 67 is provided, in its outer face, with a substantially frusto-conical recess indicated by 68 adapted to receive a clutch cone for operationally connecting the crank shaft to a transmission shaft.

As will be noted more clearly from Fig. 2 of the drawings, the end portions of the cam shaft 46 are rotatably supported by bearing members 69 and 70 mounted in the base section 1 of the casing. The bearing portion of shaft 46, at each end thereof, is provided with oppositely directed helical grooves 71, which cross and extend inwardly from collars 72 secured to the shaft adjacent the inner end of the bearing member. The inner ends of these grooves 71 terminate closely adjacent concave oil receiving members or cups 73 which are secured to the shaft 46 and project substantially radially therefrom. These members are adapted to receive oil which is projected thereon during the operation of the crank shaft, this oil being directed into the grooves 71 by means of which it is conducted onto the bearing surfaces of the end portions of the shaft. This insures proper lubrication of the bearing portions of the shaft so as to prevent looseness or excessive wear thereof.

To permit access to the gears 48 and 49, I provide a gear housing 73 which is detachably secured to the upper section 1 of the casing, this housing being in alinement with the gears. By removing housing 73, ready access to the gears is obtained as will be evident.

The foregoing description and the drawings have reference to what may be considered the preferred, or approved, form of my invention. It is to be understood that I may make such changes in construction and arrangement and combination of parts, materials, dimensions, etc., as may prove expedient and fall within the scope of the appended claims.

Having thus fully described my invention, what I claim as new and desire to secure by Letters Patent, is:

1. Oiling means for internal combustion engines comprising a crank casing having a cam shaft and crank shaft rotatably supported therein and driving connections between said crank and cam shafts, an oil pump suspended to hang within the casing below the crank shaft and being operable from said cam shaft, oil-trough means disposed beneath said crank shaft, oil feed pipes leading outwardly from said pump

and under said trough means for supporting the latter, said pipes feeding oil to said trough means through the bottom thereof, 65 dipper means provided on the crank shaft for splashing the oil from said trough means, and means provided on said cam shaft for receiving and distributing to the bearing thereof the oil splashed from said 70 trough.

2. An oiling means for internal combustion means, in combination, a crank case, a removable section constituting a main oil reservoir, separate and distinct oil troughs 75 supported transversely of said crank case, a crankshaft provided with dippers for splashing the oil from said oil troughs, an oil pump suspended from said crank case with its suction end in proximity to the 80 bottom of the removable reservoir section, oil feed pipes extending outwardly from said pump for discharging oil at the bearing portions of said crank shaft, said pipes adapted to provide supports upon which 85 the oil troughs rest, said pipes being in communication with the bottom of said troughs for supplying oil thereto and means for effecting driving connections between said 90 crank shaft and said pump.

3. An oiling attachment for internal combustion engines, comprising, in combination with a sectional crank casing having dipper bearing crank and cam shafts respectively mounted therein, of an oil pump having a 95 supporting bracket whereby it may be suspended to hang within the crank case with its suction end adjacent the crank case bottom, feed pipes carried by said pump and projecting outwardly from the discharge end thereof, with their free ends adapted for connection to the main shaft bearing, trough means rigidly supported upon each of said feed pipes and supplied with oil therefrom, said troughs being so positioned 100 upon said pipes as to lie in the path of the dipper bearing portions of the said crank shaft whereby the oil splashed therefrom may be distributed within the casing and incidentally deposited on the dipper bearing portions of the crank shaft and driving means between said cam shaft and said 105 pump, said pump, feed pipes and oil trough adapted to be suspended into the reservoir portion of said casing, free of any connection thereto, whereby said reservoir section may be removed from said casing without disturbing the said recited elements.

In testimony whereof I affix my signature in presence of two witnesses.

CLARENCE R. EATON.
